UNITED STATES PATENT OFFICE.

CHARLES FISHER, OF CHICAGO, ILLINOIS, ASSIGNOR TO INTERNATIONAL SAFE COMPANY, OF CHICAGO, ILLINOIS, A CORPORATION OF WISCONSIN.

SAVINGS-BANK.

No. 898,206.

Specification of Letters Patent.

Patented Sept. 8, 1908.

Application filed May 29, 1907. Serial No. 376,445.

To all whom it may concern:

Be it known that I, CHARLES FISHER, a citizen of the United States, residing at Chicago, in the county of Cook and State of Illinois, have invented a new and useful Improvement in Savings-Banks, of which the following is a specification.

My invention pertains particularly to savings banks adapted to be carried on the person for the purpose of inculcating in the young, particularly, habits of thrift and saving.

My primary object is to provide a savings bank of simple and inexpensive character, so well adapted to be carried in the pocket of the user as to insure its being ready at hand for use when the impulse for saving is felt and before the money is spent which might otherwise be saved.

20 A further object is to prevent withdrawal of the coin should the saving impulse of the child be succeeded by an uncontrollable desire to spend the money before the complete insertion of the coin into the savings bank.

25 I accomplish my primary object by providing a flexible receptacle, or purse-body, with a closure supplied with a coin-slot, and I accomplish the further purpose indicated by equipping the coin-slot of the savings 30 purse with a coin-gripping device which will yield to permit ingress of the coin but will firmly grip the coin in the event of an effort at withdrawal.

The invention is illustrated in its preferred 35 embodiment in the accompanying drawings, in which:

Figure 1 represents a perspective view on an enlarged scale, of my savings purse; Fig. 2, an enlarged broken sectional view taken as indicated at line 2 of Fig. 1; Fig. 3, a transverse vertical section taken as indicated at line 3 of Fig. 2; Fig. 4, a broken horizontal section taken as indicated at line 4 of Fig. 2; Fig. 5, a perspective view of a spring locking device which is applied to the interior of the closure or removable cover employed; and Fig. 6, a broken perspective view illustrating the formation of a metallic neck-portion of rectangular shape, which preferably is employed in connection with the flexible receptacle, bag or purse-body.

In the construction illustrated, A represents a flexible purse-body, bag or receptacle; A¹ a metallic rim or neck for the same provided internally at its ends with retainers

or rigid catches a; B, a cover or closure telescopically connected with the neck of the purse-body and provided with a coin-admission port or slot b; B¹, a retainer member contained within the closure B and firmly secured thereto and equipped with yielding spring retainers or catches b¹ adapted to engage the retainers a; B², a coin-gripping device guarding the coin-slot b; and C, a retainer-disengaging device or key adapted to enter the coin-slot and serving to disengage the retainers b¹ from the retainers a.

The purse-body may be of any suitable form. It preferably is formed of leather, comprising relatively wide sides a⁴; an in-folded or accordion plaited web a² forming the relatively narrow sides and bottom of the purse-body, the edges of the web being joined to the bottom and lateral edges of the sides a⁴ by stitchings a³. The upper portion 75 of the flexible purse-body is contracted somewhat and fits snugly over the main body of the metallic neck portion A¹. The part A¹ may be conveniently formed from a strip of sheet metal which is preparatorily provided in blanking dies with flanges which will now be described, the strip of metal being bent into rectangular form to form the neck. When properly blanked and formed, the metallic neck portion comprises sides a⁴ 80 provided with down-turned flanges a⁵, and ends a⁶ provided with down-turned flanges a⁷. One of the ends a⁶ is formed by overlapping the ends of the strip from which the neck portion is formed, as shown in Fig. 4, the inner end being provided with a lug a⁸ which 85

passes through an opening a⁹ with which the outer overlapping end margin of the strip is provided and is clenched, as shown in Fig. 6. The end margins of the strip are further securely joined together by providing the lower edge of the inner end margin with an upturned flange a¹⁰ which embraces the lower margin of the outer end margin, as shown in Fig. 6. The side flanges a⁵ are 90 equipped at their lower edges with prongs a¹¹, and the lower margins of the side members a⁴ are provided with openings a¹² adapted to receive said prongs. The upper portion of the bag or flexible body is slipped 95 over the body of the metallic neck portion and the flanges a⁵, a⁷ are turned down upon the leather, the prongs a¹¹ being turned in and caused to perforate the leather and pass through the perforations a¹², after which the 100 105 110

prongs are clenched upon the inner surfaces of the sides a^4 , as shown in Fig. 2. The corners of the metallic neck portion are preferably made oblique, as indicated at a^{13} to facilitate the formation of the seams of the neck portion of the bag or to make greater room for the same, as will be understood from Fig. 4. The retainers a are preferably formed by striking the metal of the end portions a^6 inwardly, as will be understood from Figs. 2 and 6. The clenching lug a^8 is formed by punching a portion of the metal of one overlapping end of the strip outwardly, as will be understood from Figs. 2 and 6. The clenching lugs a^{11} are also formed in the blanking operation in a manner which will be readily understood.

The removable cover or cap B may be formed by drawing a piece of sheet metal into the rectangular cup-shaped form shown. The member B^1 has a horizontal web portion b^2 equipped at its ends with downturned arms b^3 which carry the spring retainers b^4 . The lateral edges of the web portion b^2 are equipped with downturned flanges b^4 , which serve as strengthening flanges. The web portion b^2 is provided with a slot b^5 of greater width than the coin-admission slot b of the cap B, said slot b^5 being flanked by upturned flanges b^6 having serrations or teeth b^7 . The retainer prongs b^1 preferably incline upwardly and outwardly, as clearly shown in Figs. 2 and 5. At the ends of the slot b^5 are provided retainers b^8 which serve as a part of the permanent connection between the member B^1 and the cap B. The coin-gripping device B^2 preferably comprises a piece of flexible friction material, such as rubber or a compound of rubber, which is firmly secured between the inner surface of the top portion of the cap B and the upper surface of the web portion b^2 of the member B^1 . This rubber strip, which is comparatively thick and suitably stiff, is provided with a longitudinal slit or cut b^9 , which registers with the coin-admission port b of the cap or closure B and with the wider slot or opening b^5 of the member B^1 , being located centrally with relation thereto. The member B^2 is provided on its lower side with longitudinal slots which receive the flanges b^6 of the web portion b^2 of the member B^1 , and the teeth b^7 press upwardly into the rubber, as indicated in dotted lines in Fig. 3, tending to make the connection more secure. At the ends of the slit b^9 , the member B^2 is provided with small perforations b^{10} , through which extend lugs or retainers b^{11} which are struck down from the metal of the cap B at the ends of the coin-admission slot. The extremities of said retainers b^{11} are permanently engaged with the retainers b^8 of the member B^1 . Thus, it will be understood, the flexible member B^2 is firmly secured between the

member B^1 and the inner surface of the top or cap B.

The retainer-disengaging member or key C is preferably formed by bending a small steel spring metal bar into the general U-shape shown in Fig. 2, the side members thus formed being provided with inwardly-struck inclined portions c adapted to engage the ends of the slot b in the event that the key is inserted beyond the position shown in Fig. 2, and depending from said inclined portions are portions c^1 which carry upwardly and outwardly inclined prongs c^2 adapted to engage the inclined retainer prongs b^1 , thereby to disengage said retainer prongs from the retainers a when an outward pull of the key C is exerted. It will be understood that the prongs c^2 pass between the retainers a shown in Fig. 6 when the closure B is removed by the use of the key. Preferably, the extremities of the members c^2 are so shaped as to afford wedges c^3 which bear against the inner surfaces of the ends a^6 and against the inclined prongs b^1 , thereby facilitating the disengaging operation.

The manner of use will be readily understood from the foregoing description. The parts are assembled in an obvious manner, the member B^2 being placed within the cap B with the retainers b^{11} passing through the perforations b^{10} ; the member B^1 is then inserted within the cap B and the extremities of the retainers b^{11} are bent to engage the retainers b^8 . In use, the coin is inserted through the coin-admission port b , the retaining lips of the member B^2 being forced downwardly by the coin, the wider opening of the slot b^5 permitting this action. Any effort to remove the coin after partial insertion causes the retaining lips of the member B^2 to grip the coin tightly, as will be understood. When it is desired to take the contents from the receptacle, the key C is inserted through the coin-admission port of the closure, the member yielding to permit this action, and the prongs c^2 are brought into engagement with the spring retaining-prongs b^1 , after which an outward pull upon the key will disengage the retaining prongs from the retainers a and withdraw the closure from the neck of the purse-body. When the closure is removed from the purse-body, the key may be forced wholly through the coin-slot, and the parts may be reassembled by simply pressing the closure on to the neck of the purse-body.

A savings-purse constructed as set forth is well adapted to be carried in the pocket of the user, and is thoroughly effective for its purpose. Moreover, such a savings purse can be cheaply constructed and is very secure.

The foregoing detailed description has been given for clearness of understanding only

and no undue limitation is to be understood therefrom.

While all of the features of construction herein illustrated and described were devised particularly for savings-purses, certain of said features may be employed in savings-banks generally.

What I regard as new, and desire to secure by Letters Patent, is:

10 1. In means of the character set forth, the combination with a receptacle, of a closure, a coin-admission port and a coin-gripping device comprising a flexible member provided with a slit registering with said coin-admission port.

15 2. The combination with a receptacle having a neck equipped with a retainer, of a closure having its top provided with a coin-slot, a retainer carried by said closure adapted to engage said first-named retainer, and coin-gripping means interposed between the top of said closure and said second-named retainer.

20 3. The combination with a receptacle equipped with a retainer, a closure provided with a coin-slot of given width, a flexible coin-gripping member having a slit registering with said coin-slot, a member beneath said coin-gripping member having a slot of greater width than said coin-slot, and retaining means carried by said closure and adapted to engage said first-named retainer.

25 4. The combination with a receptacle having a substantially rectangular neck equipped at its ends with retainers, a closure telescopically joined to said neck and having its top provided with a coin-slot, and a retainer carried by said closure having arms provided with yielding retaining members adapted to engage said first-named retainers.

30 5. The combination with a receptacle having a neck portion equipped internally with retainers, a closure telescopically connected with said neck portion and provided with a coin-slot, a flexible coin-gripping member having a slit registering with said coin-slot and provided on its lower surface with grooves, and a member provided with a slot wider than said coin-slot and having flanges engaging said grooves, said last-named member being provided with arms equipped with yielding retaining-prongs, for the purpose set forth.

35 6. The combination with a flexible purse-body, of a metallic neck portion having a body portion adapted to receive the upper portion of the flexible purse-body and having flanges folded down upon the flexible material, and a closure telescopically connected with said neck portion and provided with a coin-slot, for the purpose set forth.

40 7. The combination with a flexible purse-body, of a neck comprising a metal strip bent into rectangular form and having its upper edges equipped with downturned flanges, the

45 upper portion of the flexible purse-body being received between said flanges and the body of the metal neck, and a closure telescopically connected with said neck and having a coin-slot equipped with coin-gripping means, for the purpose set forth.

50 8. The combination with a flexible purse-body, of a metal neck comprising a strip of metal bent into rectangular form and having overlapping end margins forming one end of the neck-body, one of said overlapping portions having a perforation and the other having a lug extending through said perforation and clenched, the upper edges of said neck being equipped with downturned flanges provided with clenching lugs, the upper portion of the flexible purse-body receiving the body of said neck portion and said flanges being turned down over the flexible material and said clenching lugs clenched to secure the parts together, and a closure telescopically connected with said neck portion and having at its top a coin-slot and provided internally with retaining means serving to engage the metallic neck portion of the purse-body, for the purpose set forth.

55 9. The combination with a receptacle provided with a rigid neck portion equipped internally with retainers, of a closure telescopically connected with said neck portion and equipped internally with retainers engaging said first-named retainers, said closure having its top provided with a coin-slot, and retainer-disengaging means comprising a member of general U-shape, having retainer engaging prongs, for the purpose set forth.

60 10. The combination with a receptacle provided with internal retainers, of a closure connected therewith and equipped with internal retainers and provided with a coin-slot, and retainer-disengaging means comprising a member having spring arms equipped with retainer engaging prongs, for the purpose set forth.

65 11. In means of the character set forth, the combination of a receptacle having a neck-portion equipped with internal retainers, and a slot-equipped closure telescoping with said neck-portion and provided internally with retainers engaging said first-named retainers.

70 12. In means of the character set forth, the combination of a receptacle having a neck-portion equipped with internal retainers, a closure telescopically connected with said neck-portion and provided with a coin-slot, movable retainers within and carried by said closure, and retainer-disengaging means insertible through said coin-slot, for the purpose set forth.

75 13. The combination with a flexible purse-body, of a rigid hollow neck-portion connected therewith and a cap having flanges fitting over said neck-portion and provided in its top with a coin-slot.

80 14. The combination with a flexible purse-

body, of a rigid hollow neck-portion connected therewith, and a cap having a coin-slot in its top and equipped internally with retainers secured to said neck-portion.

5 15. The combination with a flexible purse-body, of a rigid hollow neck-portion connected therewith, a closure telescopically connected with said neck-portion and pro-

vided with a coin-slot, an internal unexposed catch connecting said closure and neck-portion, and catch-releasing means insertible through said coin-slot. 10

CHARLES FISHER.
